UNITED STATES PATENT OFFICE.

MARY M. WELSH, OF MCGILL, NEVADA.

CURTAIN-ROD.

1,399,678.

Specification of Letters Patent.

Patented Dec. 6, 1921.

Application filed April 8, 1919. Serial No. 288,525.

To all whom it may concern:

Be it known that I, MARY M. WELSH, a citizen of the United States, residing at McGill, in the county of White Pine and State 5 of Nevada, have invented new and useful Improvements in Curtain-Rods, of which the following is a specification.

This invention relates to curtain poles and has for its object the provision of a pole 10 which may or may not be extensible and which carries at its ends a suitable ornamentation in the form of a ball or similar object and removably secured thereon to facilitate the insertion of the pole within the 15 stem of the curtain.

In the use of extensible curtain poles of the character made of telescopic tubular sections, it is impossible to insert the pole within the hem of the curtain without separating 20 the sections and threading the hem over the opening near the end of one or both sections. These ends usually have more or less sharp edges, which tear or cut the threads of the delicate curtain fabric during this operation 25 and for the purpose of overcoming this objectionable feature, the present invention provides an extensible curtain rod in which one or both of the balls or ornaments usually provided upon the outer ends of the rod is 30 removable, so that the curtain may be readily slipped over the end of the rod without danger of injury to the fabric.

With the above objects in view, the invention comprises a pole, one end of which 35 is tapered and formed with a stop or shoulder spaced from the end, said end receiving a ball or ornament, which is removably held in position through the medium of the stop or shoulder, the tapered end of the pole 40 serving to center the ball or ornament and to aid in threading the curtain over the pole.

Other novel features of the invention will appear as the following description is read in connection with the accompanying drawings.

In the drawings:

Figure 1 is a longitudinal sectional view of a pole of the telescopic type provided with balls or ornaments at each end thereof, one 50 of said balls or ornaments being removably positioned upon the pole.

Fig. 2 is a sectional view through the ball or ornament detached from the pole.

Referring to the drawings in detail, like 55 characters of reference denote corresponding parts throughout the several views.

In the use of the invention, the pole may be either of the solid or extensible type, the latter being illustrated. It comprises two sections 10 and 11, the latter having permanently secured thereon a ball or ornament 12, from which projects a radial extension 13, the ball and extension serving to add to the appearance of the pole. The section 10 telescopes over the section 11, both of which 60 are preferably formed of tubular metal, the pole thus being adjustable to windows of different widths. The outer end of the section 10 carries a ball or hollow sphere 14, which in appearance is similar to the ball 12, 70 previously mentioned. The ball 14 is provided with an opening 15 for the reception of the end of the section 10 and located diametrically opposite this opening is a seat or depression 16. The extremity of the section 10 is tapered, as shown at 17, so that the end of the section may be inserted within the opening 15, with the tapered extremity seated in the seat or depression 16. The ball 14 is provided with an extension 18, similar 80 to the extension 13, previously mentioned.

Spaced from the tapered extremity 17 of the section 10, is a stop or shoulder 19, so that when the end of the section is inserted through the opening 15, the surrounding 85 edges of the said opening may be sprung over the stop or shoulder 19 and the ball removably held in position. When it is desired to insert the pole within the hem of the curtain, the ball is removed and the pole 90 threaded through the hem, the tapered extremity serving to facilitate this operation, as well as to center the ball upon the pole.

It will be observed from the drawings that the circumferential portion 19 is spaced from the end of the tapered portion a distance slightly greater than the diameter of the spherical member, causing the tapered portion to maintain its position in the seat when subjected to strain tending to cause relative 100 angular movement.

While the invention is illustrated as applied to an extensible pole, it is obvious that the same may be used in connection with a slotted pole, the removal of the ball permitting of the insertion of the pole within the hem of the curtain, an operation which would be impossible with a slotted pole were the ball not removable.

Various other changes may be made in the 110 form, proportions and minor details of construction and the right is herein reserved to

make such changes as properly fall within the scope of the appended claim.

Having described the invention, what is claimed is:

- 5 A curtain pole comprising a rod or pole, a hollow spherical member having an opening in one side for the reception of the end of the pole, a hollow projection extending from the spherical member diametrically opposite the opening and providing a seat, a tapered extremity formed on the pole and engageable with said seat and a circumferential
- 10 shoulder formed on the pole and spaced 15 from the tapered extremity for removably holding the spherical member in position the circumferential portion being spaced from the end of the tapered portion a distance slightly greater than the diameter of the 20 spherical member, causing the tapered portion to maintain its position with reference to the seat when subjected to strain tending to cause relative angular movement.

In testimony whereof I affix my signature.

MARY M. WELSH.
